MacKellar, Smiths & Jordan, 606-614 Sansom Street, Philadelphia.

UNITED STATES PATENT OFFICE.

CHARLES H. BEELER, JR., OF PHILADELPHIA, PENNSYLVANIA, ASSIGNOR
TO MACKELLAR, SMITHS & JORDAN, OF SAME PLACE.

DESIGN FOR PRINTING-TYPE.

SPECIFICATION forming part of Design No. 13,072, dated July 25, 1882.

Application filed May 26, 1882. Term of patent 14 years.

To all whom it may concern:

Be it known that I, CHARLES H. BEELER, Jr., of the city and county of Philadelphia, Pennsylvania, (assignor to MACKELLAR, SMITHS & JORDAN,) have invented and produced a new and original Design for a Font of Printing-Type, of which the following is a specification.

The nature of my design is clearly shown in the accompanying typographic impression, to which reference is made; and it consists of an unshaded condensed letter, somewhat of the style known as "Old Style," having the heavy triangular termination at top and bottom, as shown in most of the letters, and the termination with inclined side, as in the C, E, F, G, L, S, T, and Y. In the A and H the light hori-

zontal line is employed, and in the M one of the lines (the right-hand one) connecting the up and down portions of the letter is lighter than the left-hand one. The lower portions of the U, V, and W are flattened out and concaved, as shown. The character of the design is preserved in the numerals.

Having now set forth my invention, what I claim as new is—

The design for a font of printing-type, substantially as shown and described.

CHARLES H. BEELER, JR.

In presence of—

C. F. HUCH,

HERMAN METIUS.
